UNITED STATES PATENT OFFICE.

FRED RAPP, OF ALBANY, NEW YORK, ASSIGNOR OF ONE-HALF TO FREDERICK W. CONSTABLE, OF HAVERSTRAW, NEW YORK.

FOUNDATION EXTENSION.

1,331,461.

Specification of Letters Patent.

Patented Feb. 17, 1920.

Application filed January 2, 1919. Serial No. 269,178.

To all whom it may concern:

Be it known that I, FRED RAPP, a citizen of the United States, residing at the city of Albany, in the county of Albany and State 5 of New York, have invented certain new and useful Improvements in Foundation Extensions, of which the following is a specification.

My invention relates to foundation extensions for increasing or depressing the height of foundations of any style or construction and more particularly for the foundations for signal mechanism on railroads, and the object of my invention is 15 to produce simple and economical means for increasing or depressing the height of foundations, especially for signal mechanism used in connection with railways, as shown in the accompanying drawings, in which— 20 Figure 1 is a perspective view of one member of said extension.

Fig. 2 is a perspective view of another member of said extension.

Fig. 3 is a perspective view of a modified 25 form of the member shown in Fig. 2.

Fig. 4 is an end elevation, partly in section, of my extension applied to a standard foundation, and illustrates the manner of building up the extension with the various 30 members.

Similar letters refer to similar parts throughout the several views.

It is well known that in railway operations the signal apparatus is located upon foundations at various points and that changes in the road bed frequently make it necessary to elevate or depress the foundations for the signal apparatus at that point. When the road bed is elevated or depressed 40 the foundation for the signal apparatus has to be changed accordingly. The particular object of my invention is to produce a simple means by which the height of the foundation may be altered at will when desired.

Referring to the drawings, A, as shown in Fig. 1, is the main member of my extension. This member is provided with a suitable base adapted to rest upon the original foundation and having slotted holes therein, said 50 slotted holes adapted to engage with bolts for anchoring the member to the original foundation. This base portion is provided along its sides with downwardly extending flanges *a*, *a*, adapted to engage with the

original foundation if placed directly thereon, or with the sides of the top portion of a similar foundation extension if placed upon the top thereof.

The top member C of the extension A has formed longitudinally in the top thereof a *T* slot adapted to receive the head of a bolt *h* for fastening to the extension A the mechanism F, which it is desired to elevate.

In the bottom of the *T* slot I form slotted holes, in alignment with the slotted hole in the base portion. This makes it possible to fasten the mechanism F and the interposed member or members of the foundation extension securely to the original foundation by the use of one long bolt in place of two, as shown in Fig. 4.

Transverse webs, so disposed as not to interfere with clear passage between the slotted holes in the base and top members, separate and join together the top and base portions of the main extension member.

In order to provide for varying heights which may be required I provide square blocks D, E (having different thicknesses) and having a bolt hole through the center 80 thereof and on its under surface a rib adapted to fit in the *T* slot in the main extension member so as to prevent the block from turning.

Provided with my main extension members and blocks of varying thicknesses, it is a simple matter to change the height of the mechanism above the original foundation.

What I claim as my invention and desire to secure by Letters Patent is

1. In a foundation extension of the class described, a base provided with slotted holes adapted to engage with bolts for anchoring the extension to the original foundation, downwardly extending flanges longitudinal 95 of said base, adapted to engage with the top of said original foundation, a top having formed longitudinally in the face thereof of a *T* slot adapted to receive the head of a bolt, the width of said top being such that 100 it will fit between the downwardly extending flanges on the bottom of a similar extension when said similar extension is superimposed thereon; slotted holes in the bottom of said *T* slot and in line with the 105 slotted holes in said base and webs connecting said top to said base, said webs so disposed as to leave transverse openings

through the extension in which nuts adapted to engage the anchoring bolts may be manipulated.

2. In a foundation extension of the class described, a base provided with slotted holes adapted to engage with bolts for anchoring the extension; downwardly extending flanges longitudinal of said base adapted to engage with the sides of the top of a similar extension when superimposed thereon; a top having formed longitudinally in the face thereof a T slot adapted to receive the head of a bolt; slotted holes in the bottom of said T slot extending through said top and in line with the slotted holes in said base and webs connecting said top to said base, said webs so disposed as to leave transverse openings through the extension in which nuts on the anchoring bolts may be manipulated.

3. In a foundation extension of the class described, a base provided with slotted holes adapted to engage with bolts for anchoring the extension; downwardly extending flanges longitudinal of said base adapted

to engage with the sides of the top of a similar extension when superimposed thereon; a top having formed longitudinally in the face thereof a T slot adapted to receive the head of a bolt; slotted holes in the bottom of said T slot, extending through said top and in line with the slotted holes in said base; webs connecting said top to said base, said webs so disposed as to leave transverse openings through the extension in which nuts on the anchoring bolts may be manipulated, and a square block of desired thickness having a bolt hole in the middle thereof and a rib on the under side, said rib adapted to fit in the T slot formed in the said top whereby said block will be prevented from turning, all substantially as described and for the purposes set forth.

In testimony whereof I affix my signature in the presence of two witnesses.

FRED RAPP.
